UNITED STATES PATENT OFFICE.

JOHN P. WEAVER, OF TERRE HAUTE, INDIANA.

REEL-HOLDER.

No. 885,115.

Specification of Letters Patent. Patented April 21, 1908.

Application filed October 8, 1907. Serial No. 396,379.

To all whom it may concern:

Be it known that I, JOHN P. WEAVER, a citizen of the United States, residing at Terre Haute, in the county of Vigo and State of Indiana, have invented certain new and useful Improvements in Reel-Holders, of which the following is a specification.

My invention relates to certain new and useful improvements in reel holders, and the object of my invention is to improve devices of this character in which there is a spring actuated drum upon which a length of cord or chain is wound and which can be automatically held with the cord or chain unwound and which can be released so that the cord or chain will be re-wound upon the reel by a slight pull on the cord or chain.

Another object of my invention is to produce a device of this character which will be simple in construction, cheap to manufacture, positive in its operations, durable and not likely to get out of order.

With these and other objects in view my invention comprises broadly a casing within which is journaled a reel, a length of cord or chain connected to the reel, a spring adapted to rotate the reel in one direction and wind the cord or chain thereon, the reel carrying a stop with which a pawl mounted on the casing co-acts, the construction and location of the pawl being such that it is positively thrown into and out of engagement with the stop on the reel by the manipulation of the chain or cord.

The invention also consists in certain constructions, combinations and arrangements of parts the preferred form of which will be first described in connection with the accompanying drawings and then the invention particularly pointed out in the claims.

Referring to the drawings wherein I show one form of my invention and wherein the same part is designated by the same reference numeral wherever it occurs Figure 1 is a perspective view of my device with the cover separated; Fig. 2 is a rear view partly broken away; Fig. 3 is a central cross section; Fig. 4 is a perspective view of the base portion with the pawl separated; Fig. 5 is a perspective view of the reel; Fig. 6 is a sectional view showing a detail of construction.

1 designates a back plate provided with an upwardly extending flange 2, and 3 is a post secured in the center of the back plate on which the reel 4 is journaled. The back plate 1 is preferably provided with a safety pin 5

secured to the back, whereby it may be attached to the apparel of the person using the same. This pin may be secured in position in any desired manner, as by forming a depression in the back plate and soldering the back of the pin in said depression. It is evident however in the broad aspect of my invention that any other form of pin or attaching means may be substituted for the pin herein shown without departing from the spirit thereof.

6 are a pair of wires bent into U shape and passing through openings in the back plate 1, with their central portion lying in depressions 7 formed in the back plate. The central portion of these wires are preferably arranged parallel to each other with their ends extending up on each side of the central post 3. These wires are adapted to engage the free end of the coil spring by which the drum is actuated in a manner to be herein-after described. In the broad aspect of my invention the particular construction and arrangement of this means for securing one end of the helical spring is not essential, and the same may be changed or modified if desired.

8 designates a wire passing through the back plate near the periphery, one end of the wire being preferably bent into V-shape form and soldered into a similarly shaped depression in the back plate. The wire extends up adjacent to the flange 2 and on this wire is journaled a pawl 9 having its outer end centrally cut away at 10. The particular construction of the journal for this pawl and the manner of securing the same to the back plate is entirely immaterial, and may be modified or changed if desired and the particular construction of the pawl may also be modified without departing from my broad invention.

The reel 4 is preferably constructed with a central sleeve 11 adapted to be rotatably mounted upon the central post 3. To one end of this sleeve is secured the disk 12, and spaced from the disk 12 by means of the flange 13 is a similar disk 14, the disks 12 and 14 being united together by the flange 13. The flange 13 forms the drum of the reel around which a cord or chain 15 is wound, the flanges acting to keep the chain or cord upon the drum. Within the flange 13 I mount the helical spring 16, one end of which is connected to the inner side of the flange 13 and the other end of which is provided with a hooked portion 17 adapted to engage one

or more of the projecting pins 6, whereby the inner end of the spring is secured to the back plate.

In the periphery of the flanges 12 and 14 I cut notches 18 with which the pawl 9 is adapted to engage. The notches form stops by means of which, when the pawl is in engagement therewith, the reel is prevented from rotating under the influence of the spring. I have shown two pairs of notches in the drawing, but it is understood that only one pair is necessary, though more than two pairs may be provided if desired. It may also be observed that in my invention as broadly considered the character and location of these notches is not essential, as all that is required is that the drum carry a stop with which the pawl may co-act to hold the drum against rotation under the influence of the spring. The drum is placed in position by engaging the looped end 17 of the spring with the projecting ends of the U-shaped wires 6 and passing the sleeve 11 over the central post 3. The cord or chain 15 is then passed out through the notch 10 in the pawl 9.

19 is a cover plate provided with the flange 20 adapted to pass over the flange 2 of the back plate and this cover is preferably provided with some means for securing it in place. As shown this means consists of the projections 21 on the inner side of the flange adapted to engage corresponding depressions 22 in the flange 2.

23 is a central projection on the inner face 35 of the cover adapted to engage a central perforation 24 in the plate 12 of the reel, to assist in centering the same, and also to prevent the cover pressing against the face of the disk 12. In the flange 20 I provide an opening 25 through which the cord or chain passes from the reel. The opening, as shown, is in the form of an open slot in order to simplify the assembling of the parts.

In the operation of my device, when the parts are assembled as described, and the chain or cord is pulled in the direction indicated by the full lines in Fig. 1, the pawl 9 will be held out of engagement with the stops 18. When, however, the chain or cord 50 is moved to the position shown in dotted lines in Fig. 1, and the spring is permitted to wind up upon the drum, the pawl will, by the action of the chain or cord, be drawn into contact with the stop and the drum will be held in opposition to the pull of the spring.

When it is desired to wind the chain upon the reel it is only necessary to pull the chain slightly in the direction shown in full lines in Fig. 1, when the pawl will be lifted out of engagement with the stop and the spring permitted to wind the chain or cord upon the drum.

While I have described what I believe to be the preferred form of my invention, I desire 65 to have it understood that many changes can

be made in the form, construction and arrangement of parts within the scope of the appended claims without departing from the spirit of my invention.

In the claims I use the term "cord" to denote the part 15, but it is to be understood that by the term "cord" I mean to include not only what is strictly a cord, but also a chain or other flexible device which may be used if desired. 70

What I claim as new and desire to secure by Letters Patent is

1. A reel holder comprising a casing, a reel journaled within the casing, a spring adapted to rotate the reel in one direction, a cord adapted to be wound up on the reel and means for holding the reel, said means being adapted to be drawn into and out of engagement with the reel by the cord. 80

2. A reel holder comprising a casing, a reel journaled within the casing and provided with a stop, a spring adapted to rotate the reel in one direction, a cord adapted to be wound upon the reel and a pawl pivoted to the casing and adapted for engagement with the stop, said pawl being adapted to be drawn into and out of engagement with the stop by the cord. 85

3. A reel holder comprising a casing, a reel journaled within the casing and provided with a stop, a spring adapted to rotate the reel in one direction, a cord adapted to be wound on the reel, a pawl pivoted to the casing and adapted for engagement with the stop, said pawl being provided with a notch 95 in its outer end, the pawl being positioned and arranged so that the cord will pass through the notch thereof and the movement of the cord will throw the pawl into and out of engagement with the stop. 100

4. A reel holder comprising a casing, a reel journaled within the casing and provided with a notch in its periphery, a spring adapted to rotate the reel in one direction, a cord adapted to be wound on the reel, and a pawl pivoted to the casing and adapted for engagement with the notch, said pawl being adapted to be drawn into and out of engagement with the notch by the cord. 105

5. A reel holder comprising a casing, a reel journaled in the casing and provided with a notch in its periphery, a spring adapted to rotate the reel in one direction, a cord adapted to be wound on the reel, a pawl provided with a notch in its outer end pivoted to the casing and arranged for engagement with the stop, said pawl being positioned and arranged so that the cord will pass through the notch in the pawl and the pawl be thrown into and out of engagement with the notch in the reel by the movement of the cord. 115

6. A reel holder comprising a back plate, a central post rigidly secured to the back plate, a staple extending through the back plate adjacent to the post, a reel journaled on the 120

130

post, a helical spring located within the reel and having its ends connected with the staple and the reel respectively.

7. A reel holder comprising a back plate, a central post rigidly secured to the back plate, a pair of staples extending through the back plate, one staple being located on each side of the post, a reel journaled on the post, a helical spring located within the reel and

having its ends connected with the staples 10 and the reel respectively.

In testimony whereof I affix my signature in presence of two witnesses.

JOHN P. WEAVER.
